US00D822315S

(12) United States Design Patent (10) Patent No.: US D822,315 S
(45) Date of Patent: * Jul. 10, 2018

(54) FOOD PRODUCT

(71) Applicant: Mars, Incorporated, McLean, VA (US)

(72) Inventors: Guy Heath, Batley (GB); Kay Brown, Batley (GB); Kelly Stevens, Batley (GB); Gemma Monaghan, Batley (GB)

(73) Assignee: Mars, Incorporated, McLean, VA (US)

() Term: 15 Years

(21) Appl. No.: 29/587,631

(22) Filed: Dec. 14, 2016

(51) LOC (11) Cl. 01-01

(52) U.S. Cl.

USPC D1/122

(58) Field of Classification Search

USPC D1/100–130, 199; 426/104, 108, 138, 426/391, 549, 808, 94, 143, 559, 560; D11/40, 43, 79; D24/101–104; 446/118, 446/128; D21/484, 499, 503, 756, 622; D14/212, 218; D23/393, 422; D30/160; D25/119, 122; D8/354, 382; D26/138; D15/138; 52/254, 843; D7/300.2

(57) CLAIM

The ornamental design for a food product, as shown and described.

DESCRIPTION

FIG. 1 is a front right perspective view of a food product showing our new design;

FIG. 2 is a front elevation view of the food product shown in FIG. 1;

FIG. 3 is a rear elevation view of the food product shown in FIG. 1;

FIG. 4 is a right side elevation view of the food product shown in FIG. 1;

FIG. 5 is a left side elevation view of the food product shown in FIG. 1;

FIG. 6 is a top plan view of the food product shown in FIG. 1; and,

FIG. 7 is a bottom plan view of the food product shown in FIG. 1.

The broken lines shown in FIGS. 1-7 illustrate portions of the food product that form no part of the claimed design.

1 Claim, 3 Drawing Sheets
